US0D1059883S

(12) **United States Design Patent** (10) Patent No.: **US D1,059,883 S**
(45) Date of Patent: ** Feb. 4, 2025

(54) **ANGLED CORNER JOINT**

(71) Applicant: **VEGO INNOVATIONS, INC.**,
Tomball, TX (US)

(72) Inventor: **Guangyuan Xiong**, Houston, TX (US)

(73) Assignee: **VEGO INNOVATIONS, INC.**,
Tomball, TX (US)

(**) Term: **15 Years**

(21) Appl. No.: **29/839,950**

(22) Filed: **May 25, 2022**

(51) LOC (15) Cl. **08-05**

(52) U.S. Cl.

USPC **D8/354**

(74) Attorney, Agent, or Firm — Locke Lord LLP; Tim Tingkang Xia, Esq.

(57) **CLAIM**

The ornamental design for an angled corner joint as shown and described.

DESCRIPTION

FIG. 1 is a first perspective view of an angled corner joint according to my new design, wherein the first perspective view is viewed from a first direction toward an outer surface of the angled corner joint;

FIG. 2 is a second perspective view thereof, wherein the second perspective view is viewed from a second direction toward the outer surface of the angled corner joint;

FIG. 3 is a third perspective view thereof, wherein the third perspective view is viewed from a third direction toward an inner surface of the angled corner joint;

FIG. 4 is a front view thereof;

FIG. 5 is a rear view thereof;

FIG. 6 is a right side view thereof;

FIG. 7 is a left side view thereof;

FIG. 8 is a top plan view thereof; and,

FIG. 9 is a bottom plan view thereof.

1 Claim, 9 Drawing Sheets
